UNITED STATES PATENT OFFICE.

ERIC HERMAN ERICSON, OF OSCARSHAMN, SWEDEN.

CANE-GUN.

SPECIFICATION forming part of Letters Patent No. 628,142, dated July 4, 1899.

Application filed November 18, 1897. Serial No. 659,060. (No model.)

To all whom it may concern:

Be it known that I, ERIC HERMAN ERICSON, a subject of the King of Sweden and Norway, and a resident of Köpmansgatan 301, in the 5 city of Oscarshamn, Sweden, have invented a new and useful Improvement in Gun-Canes, (for which I have obtained patents in Sweden, No. 8,067, dated October 1, 1896; in England, No. 14,109, dated June 5, 1897, and in Norway, No. 5,812, dated June 2, 1897,) of which the following is a specification, reference being had to the drawings accompanying and forming a part of the same.

This invention relates to improvements in 15 gun-canes, and has for its principal object to provide a cheap and reliable gun-cane in which the handle containing the breech-block may after having opened the breech be turned backward alongside the barrel, so as to be out 20 of the way while the gun is being loaded or unloaded.

The invention consists in the construction and combination of parts hereinafter described and claimed.

25 In the accompanying drawings, in which the same letters of reference indicate the same parts in all the views, Figure 1 is a longitudinal section of the handle end of a gun-cane according to this invention. Fig. 2 30 is an end view of the same. Fig. 3 is a side view with the handle turned forward. Fig. 4 is a plan-view of the same, and Fig. 5 is an end view with the handle removed.

The handle end of the barrel *a* is provided 35 with a socket or hoop *b*, fastened by means of a screw *c*, extending into a groove *d*, which partly surrounds the barrel in such a manner that the said socket may be turned about a quarter of a revolution around the barrel of 40 the gun. Said socket is on one side provided with a projection *e*, in which the handle *f*, which also constitutes the breech-block of the gun, is so pivoted that the same may be turned from a position at about a right angle with the 45 barrel of the gun when the breech is closed, as shown in Fig. 1 by full lines and in Fig. 3 by dots and dashes, to a position about parallel with the barrel when the breech is open for loading or the like, as shown in Fig. 3.

50 The end of the barrel is outside provided with two outwardly-directed side projections or lugs *g*, placed diametrically opposite each other, preferably extending nearly a quarter of a revolution around the barrel. The breech-block is provided with two similar inwardly-

directed projections *h*. Said projections *g* and *h* are adapted to pass each other when the breech is being closed, and when the handle and socket are turned about ninety degrees, to the position shown in Figs. 1 and 2, 60 the said inward projections *h* in the breech-block pass behind the said outward projections *g* of the barrel, so that the breech is locked. By turning the handle *f* and socket *b* about a quarter of a revolution around the 65 axis of the barrel, from the position shown in Figs. 1 and 2 to the position shown in Figs. 2 and 3 by dots and dashes, the projections *g* and *h* come out of gear, so as to pass between each other. The breech-block is thus 70 unlocked and the handle may be turned backward to the position shown in Fig. 3 by full lines. In this position the breech-block is out of the way, so that a cartridge *l* can be inserted or extricated. In the projection *f* a 75 cartridge-extractor *i* is independently pivoted, preferably around the same center as the handle, and the handle is provided with a small projection *k*, adapted to engage with the said cartridge-extractor in such a manner that the cartridge *l* is drawn out when the handle is turned backward to its extreme position. The handle is of course provided with any suitable cock, trigger, &c., for firing the gun.

85 What I claim, and desire to secure by Letters Patent, is—

In a gun-cane, the combination with the barrel, of a socket adapted to be turned around the barrel about a quarter of a revolution and 90 provided with a side projection, a handle constituting the breech-block and containing any well-known cock-and-trigger arrangement for firing the gun pivoted in the said side projection to be turned on its pivot from a position at about a right angle with the length of the barrel, when the breech is closed, to a position parallel with the barrel when the breech is fully open, and a cartridge-extractor pivoted in the said projection of the socket 100 and adapted to be actuated by the handle, substantially as and for the purpose set forth.

In testimony that I claim the foregoing as my invention I have signed my name, in presence of two witnesses, this 12th day of June, 105 1897.

ERIC HERMAN ERICSON.
